ARTIFICIAL DENTURE

George A. Wiechert, St. Albans, N. Y.

Application October 14, 1948, Serial No. 54,393

6 Claims. (Cl. 32—2)

1

This invention relates to artificial teeth and to means for comfortable and efficient mastication of food and more particularly to metallic posterior teeth having tapered drainage channels and hollow ground blades though it is noted that in some of the claims the invention is not limited to metallic teeth nor even to posterior teeth.

One object of the invention is to provide an improved device and apparatus of this kind which will provide a protected or recessed upstanding hollow ground sharp cutting edge to comminute fibrous food and will function with a minimum pressure on the supporting tissues.

Other objects of the invention are to provide an improved device of this kind which includes a hollow ground cutting blade bucco-directed so that transverse motion of the teeth will easily cause cutting of the food fibers and is substantially out of reach by the tongue.

Additional objects of the invention are to effect simplicity and efficiency in such apparatus and to provide an extremely simple device or apparatus of this kind which is economical, durable, comfortable and reliable in operation, and economical to manufacture and install in plates.

Still other objects of the invention will appear as the description proceeds; and while herein details of the invention are described in the specification and some of the claims, the invention as described in some of the broader claims is not limited to these, and many and various changes may be made without departing from the scope of the invention as described.

The inventive features for the accomplishment of these and other objects are shown herein in connection with dentures which briefly stated include a plate and a shell mounted thereon forming a tooth having an upwardly pointed blade extending in a mesio-distally direction, and anterior or posterior of the main body of the tooth.

In the accompanying drawing showing, by way of example, two of many possible embodiments of the invention,

Fig. 1 is a plan front side and elevation showing the invention as embodied in a lower plate,

Fig. 2 is an enlarged plan of a pair of teeth,

Fig. 3 is a transverse vertical sectional view showing the upstanding blade, the section being taken substantially on the line 3—3 of Fig. 2 looking in the direction of the arrows of said line; and

Fig. 4 is a transverse vertical sectional view showing other features of the teeth, the section being taken substantially on the line 4—4 of Fig.

2 looking in the direction of the arrows of said line.

The dentures include a plate 10 and sets of metallic teeth 11, secured to the plate. The invention is not limited to any particular number of teeth for they may be in composite groups of several as shown in Fig. 1. However it has been found satisfactory to employ two on each side as a combination lower molar and bicuspids 12, Fig. 10, 3, which may be interposed between conventional teeth of, for instance, porcelain. In fact satisfactory results may be obtained when only one metallic tooth is used.

The metal I prefer to use possesses strength, 15 resilience, toughness with the absence of brittleness, ability to stand severe strains and stresses, inertness to mouth fluids and yet it must be capable of being shaped with great accuracy. Many such metals are commonly called "stainless steels" and are well known to the art and usually contain substantial proportions of chromium, nickel and/or cobalt.

One such alloy is described in United States Patent 1,958,446 though my invention is not 20 limited to any particular composition of the material. Any non-metallic material possessing the above physical characteristics would be suitable.

The form of the invention as illustrated in Fig. 2 comprises a molar portion 14 and a bicuspids portion 15 constricted at the mid-portion therebetween. As shown, each extreme end portion and the mid-portion are hollow ground to form upstanding blades 16, 17 and 18. Of course the blades 16 and 18 may be omitted if desired, or, for 35 instance, the bicuspids portion 15 may be omitted and the blade 17 retained. The remaining molar portion 14 could be employed between two conventional teeth.

It will be noted that the surfaces 19 and 20 40 which meet to form the edge of the blade 17 are smooth and steep so that food which is cut by the blade is constantly forced, by additional food being cut, into the ever widening notches 21 and 22 where the food is picked up by the juices of 45 the mouth on the buccal and lingual sides.

The blades 16, 17 and 18 rise no higher than the occlusal surface 24 so that the blades are well protected and are not dangerous to the tongue.

50 The greater part of the occlusal portion on the buccal side is substantially removed to leave a more or less flat surface 25 which will not trap food. This surface 25 does not extend quite to the blades 16, 17 and 18. The occlusal surface 55 24 is slightly under-cut to form a hollow ground

edge 26 directed upwardly and buccally. This edge 26 is almost physically out of reach by the tongue and presents no hazard thereto.

The occlusal lingual surface 24 is provided with indentations 28 which provide a number of peripheral chisel edges 29 as distinguished from the hollow ground edge 16, 17, 18 and 26.

The edge 26 is shown as a straight line in Fig. 2 for clarity but it will be appreciated that the occlusal surface 24 is not usually smooth and hence in practice the undercut edge 26 will usually appear somewhat sinuous.

Tests have demonstrated that one blade between the molar and bicuspid is exceedingly efficient for mastication of foods such as meats. There is no more trouble from the clogging of food than is met with natural teeth and it in nowise endangers the tongue.

The illustrations in the drawing are merely to show the inventive features of the teeth and conventional means may be employed for securing them in the gum portions. The uppers may be metallic teeth corresponding to those shown, but ordinary porcelain uppers are generally satisfactory.

The invention claimed is:

1. An artificial metallic tooth having an occlusal surface provided with substantially round indentations on the lingual side portions of said occluded surface, the upper buccal surface being lower than the occlusal surface and nearly flat and substantially smooth, and of about the same area as the occlusal surface, said buccal surface at its lingual limit being curved upwardly and slightly outwardly to form an undercut edge with the occlusal surface.

2. A lower metallic denture having molar and bicuspid teeth, each tooth having an occlusal milling surface extending transversely from the lingual side of the tooth to about half way to the buccal side of the tooth and substantially the length of each tooth, the height of the tooth in the buccal side being lower than said surface, said denture having respectively deep buccal and lingual recesses between the teeth and a vertical hollow ground blade projecting upwardly between said teeth no higher than said surface and lying in a substantially mesio-distal plane, the extent of said surface terminating past said blade in a buccal direction.

3. A lower metallic denture having molar and bicuspid teeth, each tooth having an occlusal milling surface extending transversely from the lingual side of the tooth and substantially the length of each tooth, said denture having deep buccal and lingual recesses respectively between said teeth and a vertical hollow ground straight blade projecting upwardly between said teeth no higher than said surface and lying in substantially a mesio-distal plane, the base of said blade being between the teeth at said recesses and becoming wider toward the bottom.

4. A lower metallic denture having molar and bicuspid teeth, each tooth having an occlusal milling surface extending transversely from the lingual side of the tooth to about half way to the buccal side of the tooth and substantially the length of each tooth, said denture having deep buccal and lingual recesses respectively between said teeth and a vertical hollow ground straight blade projecting upwardly between said teeth no higher than said surface and lying in substantially a mesio-distal plane, the base of said blade being between the teeth at said recesses and becoming wider toward the bottom, and forming a wall partially bounding and dividing said recesses from each other.

5. A lower metallic denture having molar and bicuspid teeth, each tooth having an occlusal milling surface extending transversely from the lingual side of the tooth to about half way to the buccal side of the tooth and substantially the length of each tooth, said denture having respectively deep buccal and lingual recesses between the teeth and a vertical hollow ground straight blade projecting upwardly between said teeth no higher than said surface and lying in substantially a mesio-distal plane, the extent of said surface terminating past said blade in a buccal direction, the upper face of the teeth on the buccal side being below said surface and substantially flat, said recesses being bounded by mesal and distal ends of the respective teeth at each side and by the blade at the back.

6. A lower metallic denture having molar and bicuspid teeth each tooth having an occlusal milling surface extending transversely from the lingual side of the tooth to about half way to the buccal side of the tooth and substantially the length of each tooth, the upper face of the teeth on the buccal side being below said surface and substantially flat, said face and surface meeting in an undercut substantially straight edge, and upstanding substantially straight blades one at each end of the denture and one between said teeth providing blades parallel with said edge, the base of each said blade being substantially concave on each side and free from structure in buccal and lingual directions so that food cut by the blades will be cammed outwardly by the faces of the blades and meet no obstruction by the denture.
